Attorney.

UNITED STATES PATENT OFFICE.

ALBERT BRÜCKNER, OF JERSEY CITY, NEW JERSEY.

RAG DOLL.

Application filed July 21, 1921. Serial No. 489,386.

To all whom it may concern:

Be it known that I, ALBERT BRÜCKNER, a citizen of the United States, and a resident of Jersey City, in the county of Hudson and 5 State of New Jersey, have invented certain new and useful Improvements in Rag Dolls, of which the following is a specification.

This invention relates to dolls and has for its primary object to provide a doll of that 10 general character commonly known as a rag-doll which is of such construction that it will strongly resemble the more expensive dolls having bisque or china heads.

One of the important objects of this invention is to provide a head for rag-dolls having a front or face portion stamped or embossed by suitable dies from papier-mâché or other suitable composition material and a packing or stuffing confining 20 fabric constituting the top, rear and side portions of the head and to which a wig is adapted to be applied.

It is also another object of the invention to provide improved means for mounting 25 the head upon the body of the doll so that the head may be adjusted to various positions in accordance with different postures in which the doll is placed.

I propose to attain the above noted objects by means of relatively few simply constructed parts which will not add materially 30 to the selling cost of the ordinary doll of this character.

With the above and other objects in view, 35 the invention consists in the improved construction, combination and relative arrangement of the several parts, as will be herein-after more fully described, illustrated in the accompanying drawings and subsequently 40 incorporated in the subjoined claims.

In the drawings wherein I have illustrated the several practical embodiments of the invention and in which similar reference characters designate corresponding parts 45 throughout the several views,

Figure 1 is a perspective view of a rag-doll constructed in accordance with an embodiment of my invention;

Figure 2 is a perspective view showing 50 the several parts of the doll head and the bust portion in separated relation;

Figure 3 is a perspective view of the parts before the wig is applied;

Figure 4 is a rear elevation;

Figure 5 is a detail sectional view show-

ing the means for connecting the head to the body of the doll;

Figure 6 is a vertical sectional view through the head and bust portions showing a slightly modified construction, and 60

Figure 7 is a perspective view of the parts seen in Figure 6 separated from each other.

Referring in detail to the drawings and more particularly to Figures 1 to 5 inclusive, 5 designates the front or face portion of the doll head. This face portion is formed of papier-mâché or other fibrous composition material by stamping or embossing the same in a manner well known in 70 the art. The outer surface thereof is properly painted or tinted to represent the eyes, cheeks, lips and nose of the doll. The top, rear and side portions of the doll head are formed from several strips of fabric 6 which 75 are cut in proper shape and size and stitched together along their meeting edges as at 7'. These connected sections of fabric confine the packing or stuffing material 7 which may consist of hair, cotton or any other equivalent material which may be satisfactorily employed for this purpose. The lower ends of the several pieces of fabric 6 and of the face portion 5 of the doll head are secured 80

to a disc 8 by an adhesive or any other suitable means. This disc is provided with a central opening through which the bolt 9 is loosely engaged, the head of said bolt engaging the upper surface of the disc and preventing the disconnection of the bolt 90 from the disc. The shank of the bolt 9 is disposed through a central opening 11 in the top wall of the bust member 10 to which the fabric walls of the body of the doll are suitably connected. A washer 12 and a 95

wing nut 13 are engaged upon the lower end of said bolt and the wing nut is adjusted to hold the washer 12 in proper frictional engagement with the under side of the top wall of the bust member 10 so as to thereby 100 retain the doll head in any position to which it may be adjusted with respect to the body.

Upon the fabric constituting the rear and side and top portions of the head a wig indicated at 14, may be readily secured by 105 means of a suitable adhesive. In this manner, it will be seen that the improved doll head may be made very realistic, notwithstanding the fact that relatively inexpensive materials are employed in its construc- 110

tion. By proper treatment the tinted or painted surfaces of the papier-mâché face portion of the head may be given a glaze or high polish. The visual appearance of the doll head will then closely resemble a head constructed of bisque, china or other like materials heretofore employed, but unlike such materials, will not fracture or break when accidentally dropped.

10 As shown in Figure 1 of the drawings, the body, arms and legs of the doll may be of the usual construction heretofore used in dolls of this type and the completed figure may be artistically dressed.

15 By mounting the head of the doll upon the body thereof as above explained, the head can be freely rotated and disposed in any desired position. By providing a rag-doll with a movable or adjustable head, a nearer approach to reality is secured and more amusement and pleasure will be derived therefrom than when the head is secured in fixed relation to the body as is the case with the ordinary rag-doll as heretofore constructed.

20 In Figures 6 and 7 of the drawings I have shown a slightly modified form of the invention wherein the bust member 10' is of semi-spherical form and the central portion of its wall is provided with a slot 15 extending forwardly and rearwardly from the center. The disc 8' at the base of the head is of concavo-convex form, the concave surface thereof being concentric with the curvature of the wall of the bust member 10'. This disc carries the bolt 9' extending through and movable in the slot 15 and the wing nut 13' which is adjusted to hold the washer 12' in frictional contact with the wall of the bust member. Thus, in this construction, it will be seen that the head may not only be rotated upon the body of the doll but can also be shifted forwardly and rearwardly to various angular positions with respect to the longitudinal axis of the body. Therefore, when the doll is arranged in various postures the head can be angularly adjusted to the proper position in accordance therewith and thereby greatly enhance the realistic appearance of the simulation.

25 From the foregoing description considered in connection with the accompanying drawings, the construction and advantages of the several described embodiments of the invention will be readily understood. By means of the present improvements, a doll may be produced at a cost only slightly in excess of that incident to the manufacture of the ordinary rag-doll and which may, therefore, be sold at a price which is considerably less than that of dolls equipped

with movable heads which are provided in that type of doll having movably attached limbs and the head of which is constructed of bisque, china, porcelain or other relatively expensive material.

30 I have herein referred to several constructions which I have found to be very satisfactory in practical use, but it is manifest that these constructions might be modified in various minor respects. Accordingly, the privilege is reserved of resorting to all such legitimate changes in the form, construction and relative arrangement of the several parts as may be fairly embodied within the spirit and scope of the invention as claimed.

I claim:

35 1. A doll-head having a rigid face portion, fabric side portions extending backward from the side edges of the rigid face portion, and an intermediate fabric top and rear portion extending backward from the top edge of the rigid face portion, said side portions and the top and rear portion being stitched together along their lateral meeting edges and each of said fabric portions attached to the rear edge of said face portion, a wig attached to each of the fabric 40 portions, and a base disc for attaching the head to a doll-body, said face portion and each of the fabric portions being attached at their lower edges to the upper surface of said disc at the marginal edge thereof. 45

2. A doll of the character described having a head comprising a face portion of relatively rigid material and top, side and rear portions of fabric confining a stuffing material against said face portion, a wig secured upon the fabric portions of the head, a bust member having a slot in its wall and means for attaching the head to said bust member including a bolt rotatable and longitudinally shiftable in said slot, and means for fixing said bolt to the head whereby the head may be adjusted to various angular positions with respect to the body. 50

3. A doll having a body including a rigid bust member having a spherical portion projecting upwardly, a head for the doll body having a cooperating spherical depression in a lower portion adapted to slide forwardly and backwardly and turn on the spherical upper portion of the bust, and means for mounting said head upon said bust member for said bodily adjustment forwardly or rearwardly of the median plane of the doll body and for independent axial rotation in any one of its adjusted positions. 55

60 In testimony that I claim the foregoing as my invention, and I have signed my name hereunder.

ALBERT BRÜCKNER.
